UNITED STATES PATENT OFFICE.

SAMUEL S. APPLEGATE, OF CAMDEN, NEW JERSEY.

IMPROVEMENT IN CIRCUIT-CLOSERS FOR ELECTRIC ALARMS.

Specification forming part of Letters Patent No. 174,461, dated March 7, 1876; application filed June 9, 1875.

To all whom it may concern:

Be it known that I, SAMUEL S. APPLEGATE, of Camden, New Jersey, have invented an Improved Indicator and Alarm for Stores, &c., of which the following is a specification:

The object of my invention is to provide stores, offices, &c., with an economical device, through the medium of which an alarm can be given by those who pass through the doorway; and this object I attain in the manner which I will now proceed to describe, reference being had to the accompanying drawing, in which—

Figure 1 is a longitudinal section of part of the floor of a room, showing the application of my invention; Fig. 2, an enlarged sectional view of Fig. 1.

A is a platform, arranged on the floor of a room near the door-step *a*, and supported upon springs *d*, the platform being provided with a number of pins, *b*, which project through openings in the floor, and which are so arranged in respect to the spring-arms *e* of an electric signal apparatus that when the platform A is depressed a circuit will be completed and an alarm sounded. The springs *d* (shown in the drawing) consist of short sections of rubber tubing, through which the pins *b* pass, and which are secured at their upper ends to the underside of the platform A; but other springs may be employed for slightly elevating the platform above the floor, and insuring its recoil after being depressed.

The platform may be covered with rubber, cloth, or other suitable material, which extends over the edges, and has the appearance of an ordinary rug or mat, one of its main advantages being that the platform can be removed

and replaced with facility, and without disturbing the electrical mechanism through which the alarm is given.

Although my invention is intended especially for application to small stores, &c., where it is desired to call an attendant from an adjoining room upon the entrance of a customer, it may be applied with good effect to the vestibules or halls of dwellings. In this case the fact that the platform takes the place of an ordinary mat, and can be applied without mutilating the floor, is of especial advantage, as these floors are frequently made of costly marble, the injury of which consequent upon the use of ordinary forms of platforms has heretofore prevented their adoption.

I am aware that yielding boards and spring-platforms sunk in recesses in the floor have been heretofore used as indicators or alarms, and therefore do not claim the combination of the yielding platform with the electric alarm; but

I claim as my invention—

The combination of a floor having a surface free from recesses with the platform A, supported above said surface upon springs *d*, and provided with pins *b*, passing through minute openings in the floor, and connected below with the circuit-breaker of an electric alarm, all substantially as set forth.

In testimony whereof I have signed my name to this specification in the presence of two subscribing witnesses.

SAMUEL S. APPLEGATE.
